UNITED STATES PATENT OFFICE

147,439

DESIGN FOR A COMBINATION DESK UNIT

Benjamin Halprin, New York, N. Y.

Application October 26, 1946, Serial No. 134,276

Term of patent 3½ years

(Cl. D74—1)

To all whom it may concern:

Be it known that I, Benjamin Halprin, a citizen of the United States, and a resident of the city of New York, in the county of New York and State of New York, have invented a new, original, and ornamental Design for a Combination Desk Unit, of which the following is a specification, reference being had to the accompanying drawing, constituting a part thereof, in which:

Fig. 1 is a top plan view of a combination desk unit showing my new design.

Fig. 2 is a side elevation.

Fig. 3 is a front elevation.

I claim:

The ornamental design for a combination desk unit, as shown.

BENJAMIN HALPRIN.
